UNITED STATES PATENT OFFICE.

HENRY SMITH, OF CHICAGO, ILLINOIS.

CONTROL FOR CURTAIN AND AWNING ROLLERS.

Application filed March 3, 1924. Serial No. 696,564.

My invention relates to control mechanism for rollers for curtains and awnings and consists in the matters hereinafter described and then pointed out in the appended claims.

5 In the accompanying drawings Figure 1 is a front perspective view of a roller-awning embodying the features of my invention with the parts in position when the awning is lowered, one end of the roller being broken away for clearness of illustration;

Fig. 2 is a detail view partly in side elevation and partly in section showing the awning cloth rolling underneath the roller for purposes of illustration;

15 Fig. 3 is a detail longitudinal sectional view on the line 3—3 in Fig. 4, showing the locking mechanism applied to the right-hand end of the roller, the cloth being omitted;

20 Fig. 4 is an end view showing the angular end of the roller-gudgeon seated in a suitable retaining bracket;

Fig. 5 is a cross sectional view on line 5—5 in Fig. 3;

Fig. 6 is a similar view on line 6—6 in 25 Fig. 3;

Fig. 7 is a longitudinal sectional detail view, and

Fig. 8 is a view similar to Fig. 3 showing the locking mechanism applied to the left-hand end of a roller.

In the drawings the same reference numerals throughout the different views represent the same or corresponding parts, the number 1 designating a roller on which the cloth 2 of the curtain awning is wound in juxtaposition to the structure 3 to which it is applied. When a roller-awning is used it consists of a suitable length of canvas or other cloth which is fastened at its inner end upon the roller which revolves in suitable bearings or brackets 4 having their bases 5 fastened to the uprights or posts at the sides of the window 6; the outer end of the cloth is supported by an angular frame comprising a front pole or rod 7 secured to it and a pair of side arms 8 pivoted on the uprights as at 9. The roller is operated by suitable means to wind and unwind the cloth, such for example as a 35 sprocket-wheel 10 secured on one of its ends and driven by a chain 11 from a suitable hand-winch 12 mounted on the structure in convenient reach of the operator and having a pawl or dog (not shown) to prevent 40 reverse motion. In this type of installation center supports or bearings are frequently

employed to prevent the roller from sagging, these center supports generally comprising a lower bracket 13 having ball-bearings 14 for the roller and an upper retainer or cap-piece 15 to hold the roller in place, the cloth normally extending at a tangent from the upper portion of the roller, all as shown for example in Fig. 1. When a vertically moving curtain is used, as for example in 45 the proscenium arch of a theater, it is secured at its upper end to the roller, which may be hand-operated or power operated, and may have similar center supports. When a curtain is used as an ordinary house 50 or store window shade it is carried on the usual roller which is operated to roll and unroll it in the usual manner, preferably being turned in its winding-up direction by the well-known pawl-controlled spring. 55

All of these types or classes of awnings or heavy curtains as at present equipped are objectionable in that they have no means to mechanically and automatically regulate the extent to which the cloth is unwound or lowered to the desired depth. The common roller-awnings are desirable for store-fronts and other locations not only for protection to merchandise but from the comfort they afford from the sun's rays. However, it has been found in practice that the pins fastening the operating-wheel 7 to the roller frequently break or shear off, so that the supporting frame of the awning swings down and causes damage to the awning and property and injury to persons, and this liability also arises from accident to any part of the operating devices, such as the pawl or dog by which the winch 9 is usually held against the stress and weight of the canvas and its frame, and by the failure of the operator to secure the operating parts in proper relation and position. Furthermore, the ordinary life of the canvas of such awnings as now constructed is approximately only two 60 years, the cause of this rapid deterioration being due largely to the fact that when in use the canvas is often allowed to reverse itself on the roller so that its lower surface comes in contact with the center-support in 65 an unnatural position and its wear is hastened and the appearance of this surface is rapidly destroyed. For example, the length of the cloth is such that when the supporting frame is horizontal the upper end of the 70 cloth is wound more or less on the roller, and the front bar of the supporting frame leads 75

the cloth off of and onto the upper portion of the roller in a tangential path that practically clears the outer end of the center support so that there is little friction and wear on the lower surface of the canvas and only the upper surface of the canvas contacts with the lower portion of the center support, but in lowering the awning the operator frequently allows the cloth to un-
wind too far and the horizontal frame to drop below its normal horizontal position, so that when the awning is again raised the cloth will wind underneath the roller as shown in Fig. 2. The reversal of the cloth on the roller causes its lower surface to drag heavily on the outer end of the bracket 13 of the center support and to contact with it underneath the heavy roller so that it is more rapidly worn and its appearance is quickly destroyed. This is indicated by the shaded portion of the canvas in Fig. 1.

In the case of curtains (which term includes window-shades) the cloth is frequently unrolled or drawn down so far that it is torn from its fastenings to the roller. A further objection to roller awnings and curtains as now constructed is that it is difficult to secure their uniform alinement when lowered where a plurality of them are set in series alongside of each other; they hang at various elevations and inclinations, and so present an uneven and objectionable appearance.

The objects of my invention are to remedy these defects and obviate these objections. By my invention, the extent to which the roller will be rotated to unwind the cloth is controlled, and a safety device is provided which automatically limits the extent to which the curtain or awning can be lowered. In a roller-awning equipped with my invention the supporting frame can be lowered only to the desired depth, and it is automatically prevented from moving below this level; in the event of accident to any of the operating parts the awning will unroll to the extent to which the controlling device has been set, and will be automatically stopped at that point so that the supporting frame cannot swing down, thereby preventing possible personal injury and property damage. Also, my invention makes it impossible for the operator to wind the cloth on the roller in reverse direction, whereby the wear on the inside surface of the cloth is obviated and the life of the awning is prolonged, and it permits the adjustment of one or a series of awnings to be set at any angle and retain that position, whereby their alinement is automatic and constant. Further, my invention protects curtains from being drawn down to such extent as to tear them loose from their roller-fastenings, and secures uniformity and evenness of appearances. It also affords a new adjustment for

downward movement in all these instances without disassembling any of its parts or at all dismantling the curtain or awning, and by an easy manual operation while all elements are in their operating relation, and the same assembly or unit can be applied to either end of the roller.

These various advantages and novel results are obtained by a control-mechanism which comprises a chambered casing adapted to be fastened in a suitable seat in one end of the roller and having heads forming end-abutments, a gudgeon journaled in the casing and constructed at its outer end to detachably engage a retaining bracket in non-rotating relation, and co-operating devices between the gudgeon and casing whereby the revolution of the latter on the former to unwind the cloth will be automatically arrested or stopped at the desired position.

In the exemplification of the invention here shown the casing comprises a pair of complementary semi-cylindrical sections 16 and 17 of suitable metal and each provided with an interior longitudinal trough or recess terminating in shouldered ends 18 and 19, respectively; the faces of the edges and ends are flush with each other on each section, and the abutting faces make close fit when the sections are assembled together to form an inner longitudinal chamber having closed heads. The head at the inner end of the chamber formed by the end-shoulders 19 is provided with a reduced circular bearing 20 in the axial line of the chamber, and preferably also with a socket 21 of less diameter than the chamber; the head at the outer end of the chamber formed by the end-shoulders 18 is provided with a circular bearing 22 in the axial line of the chamber. The sections 19 of the inner head are also provided with a cross-bore to receive a fastening pin 23. A metallic gudgeon 24 is located in the chamber, its diameter being somewhat less than that of the chamber, and its ends being reduced to form journals 25 to fit the end-bearings 20 and 22; the end of its inner journal is formed with a circular head 26 of less diameter than the gudgeon to rotatably fit into the socket 21 and hold the gudgeon against endwise displacement; the outer end of the gudgeon projects beyond the head 18 and is angular or squared as at 27 to fit the seat in the bracket 4. The body of the gudgeon in the chamber is screw threaded, and a nut 28 has threaded engagement therewith to travel longitudinally thereon in the chamber. The nut is held against turning in the chamber and is rotated to run on the gudgeon by the revolution of the casing on the latter by any suitable arrangement; in practice I prefer to make the interior cross-section of the chamber to correspond with the size and shape of the outer surface or contour of the

nut, in the form shown these co-operating parts being hexagonal. In assembling the parts the nut is passed over the reduced head 26 and threaded onto the screw of the gudgeon, the latter with its nut is then placed in one of the sections of the casing as shown in Fig. 3, the other casing-section is placed in position on the first section, the casing is inserted in its seat in the roller, and the pin 23 is passed through the roller and inner head sections 19 of the casing to hold the parts in assembled position and in place in the roller.

When the roller and its cloth forming the curtain, shade or awning are to be placed in position, the control unit is mounted in the appropriate end of the roller and secured by the cross-pin 23 and the cloth is wound up to its limit on the roller which is then mounted in its supporting brackets, the squared end of the gudgeon being seated in a correspondingly shaped bracket 5 as shown in Fig. 4. The position of the nut on the screw of the gudgeon at this time is not important. Assuming that the roller is now turned as shown to unwind its cloth until its free edge reaches the desired elevation, the revolution of the casing on the gudgeon turns the nut on its screw to cause it to travel toward the right when the casing is in the right-hand end of the roller as in Fig. 3 and to travel toward the left when the casing is in the left-hand end of the roller as in Fig. 8. When the awning or shade is lowered to the desired extent the squared end 27 of the gudgeon is lifted out of its bracket, the roller and cloth are held in stationary relation and the gudgeon is revolved in the casing in the opposite direction to the rotation of the roller in unwinding the cloth until the nut contacts with the head 18 in the former case (Fig. 3) and with the head 19 in the latter case (Fig. 7). This locks the roller and gudgeon together so that the former cannot turn further on the latter in the direction to unwind or lower the cloth, and the parts are retained in this relation and the squared end of the trunnion is reseated in its bracket; the roller is now locked at the limit of its cloth unwinding or lowering rotation, though it is free to turn in the opposite direction to rewind the cloth upon it to raise the awning, shade or curtain. If in assembling the parts the nut is so located on the screw that it abuts against the corresponding head before the cloth is unwound to its desired position the gudgeon is raised from its seat as before and turned in the casing to cause the nut to run or travel away from this head, and then the trunnion is again seated in its bracket and cloth is unwound to the desired extent, this operation of retreating the nut away from the head being repeated if necessary, and when the cloth is

unwound to the desired extent the gudgeon is raised from its bracket and turned to set the nut against the head as above described. The end-shoulders 18 and 19 forming the heads are rigid and strong, and preferably are integral with the sections of the casing so that these parts may be formed of metal casting as shown; the heads form rigid and unyielding abutments which will successfully resist and withstand the heavy shocks and severe strains to which they will be subjected by the impact or thrust of the nut traveling under the stress of the great weight of an awning and its heavy frame or of a heavy curtain in case of accident or the neglect of an operator. Also, the head formed by the end shoulders 19 substantially fills the bore of the roller 1 as shown in Fig. 6, so that the cross-pin 23 is embedded for substantially its entire length and is not liable to bend or shear when the casing is locked against further unwinding movement of the roller.

When the awning is lowered the roller revolves on the stationary gudgeon 24 and the nut 28 travels along the thread of the gudgeon until the awning reaches its desired extended position when the nut abuts against either the head 18 or the head 19 according to whether the casing is in the right hand end or the left hand end of the roller as explained above, and when the nut reaches either of these positions it locks the casing and gudgeon together, and as the casing is held against rotation in the roller by the pin 23 and the gudgeon is held against rotation by its angular end 27 seated in the bracket 4 the roller is then held against further rotation and the awning cloth is held in its extended position and sustains the awning frame 8 in its normal horizontal position as shown in Fig. 1. Consequently the frame and cloth cannot swing down beyond their normal intended position, even if any of the operating devices break or are improperly handled.

In practice I prefer to make the abutting faces of the heads and nut so that the area of their contact will be minimized, and also so that the thread of the screw will not be jammed between them. This is accomplished by forming the nut with its threaded central portion of slightly less length than its outer surface, so that an annular shoulder 29 is provided on each end, and by forming the heads with corresponding annular shoulders 30 to register with the shoulders 29 as shown in Fig. 7. By this construction I obviate the liability of the nut to bind upon the head so tight as to require considerable force to separate them on reversing the rotation of the casing or of the gudgeon, and I prevent this distortion of the thread otherwise caused by jamming it between the head and nut.

The control is adjustable by assembling the nut on the screw at different positions away from the co-operating abutment, and it is reversible as shown in Figs. 3 and 8 to either end of the roller. In practice the thread or screw of the gudgeon is preferably about twice the length necessary to allow the curtain or awning to unroll to its usual or normal position, so that the nut can be assembled on it at such distance from the co-operating head or abutment that the nut will not meet the latter until the awning or curtain is lowered to the usual horizontal position of the awning-frame or the usual down position of the free end of the curtain, or beyond the same if desired. As the unwinding of the cloth when the awning is lowered to its normal position will be stopped before its upper end is entirely unwound from the roller the reversal of the cloth on the roller is prevented.

I claim:

1. In a device of the class described, a sectional casing having a longitudinal chamber and opposite heads integral with the casing and forming end abutments, a threaded gudgeon journaled in the heads and having an angular end projecting beyond one of the heads, a nut on the thread to abut against either head, and co-operating devices between the nut and casing constructed to rotate these parts in unison on the gudgeon to move the nut along the gudgeon to abut against one of the heads to lock the gudgeon and casing together.
2. In a device of the class described, a casing composed of sections each having a longitudinal recess and integral end shoulders constructed to form opposite end abutments and an intermediate angular chamber, a gudgeon journaled in the abutments and having a screw-thread in the chamber and provided with an angular projecting end, and a nut on the thread slidably fitting in the chamber to revolve therewith and move along the gudgeon to position against one of the abutments to lock the casing and gudgeon together.
3. In a device of the class described, a

curtain or awning roller having a seat at one end and a sectional casing in said seat and having a longitudinal chamber of irregular cross-section provided with heads having journal bearings, a gudgeon journaled in said bearings and having a screw-thread in the chamber and provided with a squared projecting end, a pin in the roller passing through one of the heads to hold the casing sections together and against rotation in the roller, and a nut on the thread slidably fitting in the chamber to rotate in unison with the casing and move along the gudgeon and abut against one of the heads.

4. In a device of the class described, a curtain or awning roller having a seat at one end, a casing in said seat and having a longitudinal chamber provided with heads having inner annular shoulders, a gudgeon journaled in said heads and having a screw-thread in the chamber and provided with a squared projecting end, a bracket co-operating with the squared end of the gudgeon to hold the latter against rotation, a nut on the thread having annular end shoulders to register with said first shoulders, and means between the casing and nut to revolve these parts in unison to move the nut along the gudgeon to abut against one of the heads.

5. In a device of the class described, a roller having a seat at one end, a sectional casing in said seat having end abutment and an intermediate longitudinal chamber, one of the abutments having a socket and a reduced bearing intermediate the socket and chamber, a gudgeon journaled in the abutments and having a head in the socket and a screw-thread in the chamber and provided with a projecting angular end, a nut on the thread, means to rotate the nut with the casing to move the nut along the thread and lock it against one of the abutments, and a pin in the roller passing through one of the abutments to hold the sections of the casing together to rotate with the roller.

In testimony whereof I affix my signature.

HENRY SMITH.
